UNITED STATES PATENT OFFICE.

WILLIAM ORR, OF TRENTON, NEW JERSEY.

WIRE-CLOTH LATHING.

SPECIFICATION forming part of Letters Patent No. 394,602, dated December 18, 1888.

Application filed November 17, 1886. Serial No. 219,119. (No model.)

To all whom it may concern:

Be it known that I, WILLIAM ORR, a citizen of the United States, residing at Trenton, county of Mercer, and State of New Jersey, 5 have invented certain new and useful Improvements in Wire-Cloth Lathing, fully described and represented in the following specification and the accompanying drawings forming a part of the same.

10 This invention relates to that general class of lathing material which is made of wire cloth or gauze.

The invention relates particularly, however, to a furring-strip, which is designed for use 15 in connection with such lathing material, and to means for securing the wire-cloth to the furring-strip and the strip to the wall or ceiling. In using this class of lathing material for walls it is usually desirable to employ fur- 20 ring, in order not only to remove the lathing a sufficient distance from the wall to permit the mortar to clinch, but also to provide an air-space between the plastering and the wall, while in the case of ceilings it is necessary to 25 use furring-strips to properly support the lathing. As one of the principal objects in using this class of lathing material is to secure a fire-proof structure, it is impracticable to employ wooden furring-strips in connection 30 with it, and as a consequence iron strips of various forms have been employed for this purpose; but all of the forms which have heretofore been proposed have been open to objections more or less serious. In some cases 35 the strips have been of such form as to not be sufficiently stiff without being too heavy. In other cases the forms have been such as to involve too great expense in their production; and in other cases they have been of 40 such form that difficulty was experienced in properly securing the wire-cloth to them. Another objection to the furring-strips heretofore proposed is due to the fact that they have afforded no ready means for stretching the 45 cloth, so as to prevent it from springing to too great an extent when the mortar was applied.

It is the object of the present invention to overcome, as far as may be, these difficulties; and to that end the invention consists in a 50 furring-strip, and in a means for attaching the strip to the wall or ceiling and the wire-cloth

to the strip, which will now be described, reference being had to the accompanying drawings, in which—

Figure 1 is a view of a portion of the wall 55 and ceiling of a room, showing the wire-cloth lathing attached thereto by means of furring-strips and fastening devices embodying the present invention. Fig. 2 is an enlarged horizontal section taken through the wall of the 60 room. Fig. 3 is an enlarged section, taken on the line $x-x$ of Fig. 1, illustrating the manner of securing the furring-strips to the beams overhead and the cloth to the strips. Fig. 4 is a view similar to Fig. 3, illustrating a modi- 65 fication in the manner of securing the cloth to the furring-strips. Fig. 5 is a section taken on the line $x-x$ of Fig. 4; and Figs. 6 to 13 illustrate various other modifications, all of which will be hereinafter explained. 70

Referring particularly to Figs. 1 to 3, it is to be understood that A represents an ordinary brick wall—for example, the wall of a room; B, the ordinary iron beams employed to support the ceiling of the room and the 75 floor of the room above; C, ordinary wire-cloth-lathing material; and D, the furring-strips which are used as a means of securing the lathing to the wall and to the beams B. The furring-strips D are composed of sheet 80 metal bent or corrugated, so as to assume substantially the shape of the letter W in cross-section. The strips D, made in suitable lengths to be conveniently handled, are placed along the wall at suitable distances from each 85 other and temporarily secured in position in any suitable manner. The wire-cloth C is then placed upon the furring-strips, it being preferably doubled under the strips at the corners, as shown at the left of Fig. 2. When 90 the furring-strips and the wire-cloth are in position, tightening-strips a, formed of two or more wires twisted together, as shown, so as to provide loops b at proper intervals, are placed along the wire-cloth over the furring- 95 strips, and suitable nails or screws, c, are passed through the loops b of the tightening-strips a, and through corresponding openings in the furring-strips, and driven into the wall. As the nails or screws c are driven into the 100 wall their heads will come into contact with the strips a and force them and the wire-

cloth into the corrugations of the furring-strips, as shown in Fig. 2, and this being continued until the nails or screws *c* are fully driven in the cloth and the furring-strips will 5 be firmly secured to the wall, and at the same time all slack will be taken out of the cloth, so as to render it sufficiently stiff and unyielding to receive the mortar. In applying the furring-strips and the wire-cloth to the 10 beams *B* to form the ceiling the furring-strips are first secured to the beams by means of clips *d*, which overlap the flanges of the beams, and are secured to the furring-strips by means of bolts *e*, as best shown in Figs. 1 and 3. 15 The cloth is then placed under the furring-strips, with the tightening-strips *a* upon its under side, and the strips and the cloth are then secured to the furring-strips by means of spring clips or hooks *f*, which are passed 20 over the tightening-strips and through the meshes of the cloth and have their ends sprung into openings in the sides of the furring-strips, as shown in Fig. 3. The clips *f* are made of spring-wire, so that they can be 25 readily sprung into position without the use of special tools or implements for the purpose, and are of such form that when in position they force the tightening-strips *a* and the wire-cloth into the corrugations of the 30 furring-strips, so as to take the slack out of the cloth the same as when the tightening-strips are held in position by means of the nails or screws.

The construction which has thus been described embodies the invention in its best form; but various modifications may be made without wholly departing from the invention. The clips *f*, instead of being of the form shown in Fig. 3, may be of the form shown in Fig. 40—that is to say, they may be elongated so as to hook over the tops of the furring-strips, instead of passing through openings in the sides of the strips—or the furring-strips, instead of being provided with openings in their sides 45 to receive the ends of the clips, may have their edges turned inward or outward, as shown in Figs. 7 and 8, so as to provide locking-flanges which will engage with the ends of the clips when the latter are sprung into position, and 50 when the furring-strips are made of this form the clips *f* will be of the form shown in Figs. 7 and 8. In either of these cases, however, the clips will perform the same function as that already described.

55 In some cases it may not be necessary to tighten the wire-cloth, or it may be desirable to tighten it by other means than by the tightening-rods *a*, and in such case the rods can be omitted and the clips *f* used alone to secure the cloth to the furring-strips, as shown in Figs. 4 and 5. The tightening-strips *a* may be made continuous; or they may be made in short or comparatively short pieces; or instead of being made of twisted wire, as shown in 60 Figs. 1 and 2, they may be formed of flat rods, as shown in Fig. 3, the rods being, if neces-

sary, provided with suitable openings or slots to receive the nails or screws.

It may not always be desirable to employ the clips *d* and bolts *e* to secure the furring-strips *D* to the beams *B*, and in such case the furring-strips can be fastened to the beams by screws *c*, as shown in Fig. 9; and when screws are thus employed they may also be passed through the tightening-strips *a*, and thus serve not only to secure the furring-strips to the beams, but also to secure the cloth to the furring-strips and at the same time effect the tightening of the cloth, as shown in Fig. 10.

The furring-strips will preferably be corrugated, so as to assume substantially the form of the letter **W** in cross-section, as by this means the strips are made comparatively light and yet are very strong and rigid, so as to sustain a great weight or resist great pressure; and in using the strips the upper or open end of the **W** will preferably be placed against the wall or the beams. The strips may, however, be reversed, as shown in Figs. 7, 8, and 13; and in some cases strips of sufficient strength may be produced by corrugating the metal, so that it will assume the shape of the letter **U** in cross-section, as shown in Figs. 11 and 12. In all cases, however, the furring-strips are so corrugated as to provide a plurality of bearing-edges for the cloth.

In some cases, also, it may not be desirable or necessary to employ the clips *f* for securing the wire-cloth to the furring-strips, and in such case the cloth may be secured to the strips by providing the strips with prongs *g*, into which single strands of the wire of the cloth can be forced when the cloth is placed in position. By then bending the prongs upward or inward the cloth will be firmly secured to the furring-strips, as shown in Figs. 11, 12, and 13.

It will not in all cases be necessary to employ two of the clips *d* and bolts *e* at each one of the beams *B*. In some cases one of the clips at each beam, as shown in Fig. 12, will be all that will be necessary.

What I claim is—

1. A furring-strip for use with wire-cloth lathing, consisting of a strip of sheet-metal corrugated longitudinally, so as to present a plurality of bearing-edges for the lathing, substantially as described.

2. The combination, with the flanged beams *B*, of a furring-strip, *D*, made of sheet metal and corrugated longitudinally, so as to provide a plurality of bearing-edges for the lathing, the clips *d*, engaging with the flanges of the beams and with the furring-strip, and the bolts *e*, for securing the clips to the strip, substantially as described.

3. The combination, with the furring-strip *D*, having a plurality of bearing-edges for the wire-cloth, of the wire-cloth *C*, and the clips *f*, formed to engage with the furring-strip to

secure the cloth thereto and to extend inward between the bearing-edges of the strip, so as to press the cloth inward over said edges to stretch the same, substantially as described.

5 4. The combination, with the furring-strips D, each having a plurality of bearing-edges for the wire-cloth, of the wire-cloth C, secured at its ends and stretched across the furring-strips, and the tightening-strips *a*, and means
10 for forcing said tightening-strips between the

bearing-edges of the furring-strips, whereby the wire-cloth lathing is tightened, substantially as described.

In testimony whereof I have hereunto set my hand in the presence of two subscribing 15 witnesses.

WILLIAM ORR.
